Primary Examiner — Elizabeth Albert*Assistant Examiner* — Kelley Donnelly(74) *Attorney, Agent, or Firm* — Muncy, Geissler, Olds & Lowe, PLLC**(57) CLAIM**

I claim the ornamental design for a basket, shown and described.

DESCRIPTION

FIG. 1 is a perspective view of the basket showing my new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The broken lines showing the mesh surface and the top and bottom center edges on all four sides in FIGS. 1-7 are for the purpose of illustrating the environment of the design and form no part of the claimed design.
